UNITED STATES PATENT OFFICE.

GEORGE A. CONRAD, OF DETROIT, MICHIGAN.

FUSE-CARTRIDGE.

1,377,398.

Specification of Letters Patent. Patented May 10, 1921.

Application filed November 18, 1918. Serial No. 262,996.

To all whom it may concern:

Be it known that I, GEORGE A. CONRAD, citizen of the United States, residing at Detroit, county of Wayne, State of Michigan, have invented a certain new and useful Improvement in Fuse-Cartridges, and declare the following to be a full, clear, and exact description of the same, such as will enable others skilled in the art to which it pertains to make and use the same, reference being had to the accompanying drawings, which form a part of this specification.

My invention relates to a fuse cartridge shown in the accompanying drawings and more particularly described in the following specification and claims.

One of the objects of this invention is to provide a simple and inexpensive fuse cartridge in which the fuse when "blown" may be easily replaced at a minimum cost.

Another object of the invention is to provide a construction adapted to arbitrarily control the maximum cross-sectional area of the fuse strip that may be inserted in the cartridge, in order that no fuse strip capable of carrying a greater amperage may be inserted through accident or design than was originally designed for the installation in which it was employed.

Another object of the invention is to eliminate all screw-caps or other like contrivances employed in devices of this character for engaging the ends of the fuse strips to secure them in position within the cartridge.

Another feature of the invention consists of a divided insulating support for the fuse strip secured together by metal caps which engage the respective ends of the divided insulation to grip the fuse strip between the same and also to serve as terminals for the ends of the fuse strip.

Another feature is the construction of the caps themselves, which may be struck up out of sheet metal with a projecting tongue to adapt the cartridge to be gripped between the opposing springs of a fuse board (not shown).

With the foregoing and other objects in view, which will appear as the description proceeds, the invention resides in the combination and arrangement of parts and in

the details of construction hereinafter described and claimed, it being understood that changes may be made in the precise embodiment of the invention herein described without departing from the spirit of the same.

In the drawings accompanying this specification:

Figure 1 is a side elevation of a fuse cartridge embodying my invention.

Fig. 2 is a longitudinal central sectional view of the same.

Fig. 3 is a longitudinal sectional view with the end caps removed and the divided insulating portion separated to show the projecting ribs of one member of the insulating portion.

Fig. 4 is a longitudinal central sectional view of the fuse cartridge, showing the end caps provided with a projecting tongue to adapt them to be engaged by a fuse board having opposing spring terminals.

Fig. 5 is a cross-sectional view through Fig. 2 to show the projecting ribs of one member of the insulating portion extending into recesses in the other member of the divided insulating portion,—between which is lodged the fuse strip.

Fig. 6 is a fragmentary perspective view showing the construction of the end cap disclosed in Fig. 4.

Fig. 7 is a modification of the end cap in which the projecting tongue is brazed to the body portion.

Fig. 8 shows a sheet metal blank from which the cap shown in Fig. 6 is constructed.

Fig. 9 is a perspective view of one part of the insulating portion showing a fuse strip lodged between the ribs thereof,—the ends of the strip being bent over the end of the insulation in position to receive the end engaging caps.

Referring now to the letters of reference placed upon the drawings:—

A, denotes a fuse cartridge, comprising a divided insulating portion B, B, one part of which is provided with projecting ribs b, b, spaced an arbitrary distance apart—adapted to enter corresponding recesses in the opposing face of the other part of the insulating portion.

C, indicates a fuse strip lodged between

the ribs b , b ,—the space between the ribs controlling the maximum width of the fuse strip that may be lodged between them. The fuse strip is gripped between the ends 5 of the opposing parts of the insulating portion and its projecting ends, bent to overlap the end of the insulation,—with a return bend against the outer peripheral surface of the latter as indicated at C^1 . E , design- 10 nate metallic caps which engage the ends of the divided insulating portion to bind them together,—the caps serving also as terminals for the ends of the fuse strip upon which they impinge. The divided insulating portions 15 B , B are provided at opposite sides of the fuse strip C with recesses 1 and 2 extending longitudinally of the said insulating portions and terminating short of the ends thereof. The recess 1 is located between the longitudinal ribs b and the recess 2 is preferably 20 extended laterally to receive the longitudinal ribs b when the insulating portions are assembled. The ends of the abutting curved portions 3 of the cap E are designed to be 25 soldered, brazed or otherwise secured together to prevent expansion of the cap.

Instead of constructing the ribs b , b , of the divided insulating member "continuous" from end to end thereof; they may be 30 of any other preferred construction.

It will be understood that the cross-sectional area of the fuse strip controls the amperage carried thereby;—it will also be evident that the space between the ribs of 35 the divided insulating member controls the maximum "width" of the fuse strip which may be inserted therein,—while the end caps which engage the divided insulated member serve also to control the "thickness" of the 40 fuse strip lodged between the latter. It is therefore evident that if the fuse is too "thick" the caps cannot be placed over the ends of the insulating member and if too "wide" the fuse strip cannot be lodged between the ribs;—thus a fuse strip cannot be 45 inserted in the cartridge capable of carrying greater amperage than that designed therefor.

As shown in Figs. 4 and 6 the caps E may 50 be formed of sheet metal struck from a blank as indicated in Fig. 8, and may be provided with a projecting tongue E^1 , adapted to be gripped between the opposing springs of a fuse board (not shown). Instead of forming the tongue E^1 as just described, it may be a separate piece brazed to the body of the cap as shown in Fig. 7.

Having thus described my invention, what I claim is:

60 1. A fuse cartridge comprising an insulating member divided longitudinally with one portion provided with projecting ribs spaced apart adapted to enter co-acting recesses in the opposing portion of said insulating mem-

ber, a fuse strip lodged between the spaced 65 ribs and engaging the inner faces and terminals of the same and extending beyond the ends of the insulating member, and means adapted to embrace the respective ends of the divided insulating member adapted to bind 70 the parts together to form a single unit and also to serve as terminals for the fuse strip.

2. A fuse cartridge comprising an insulating member divided longitudinally having one portion provided with projecting ribs 75 spaced apart adapted to enter corresponding recesses in the opposing portion of the divided insulating member, a fuse strip located between the ribs and between the opposing portions of the divided insulating 80 member engaging the said ribs at the inner faces and ends of the same and having its ends extending beyond the ends of the latter with a return bend adjacent to its outer peripheral surface, and a pair of annular 85 caps adapted to embrace the ends of said divided insulating member to bind the parts together and to serve as terminals for the ends of the fuse strip.

3. A fuse cartridge comprising an insulating member divided longitudinally having one portion provided with projecting ribs 90 spaced apart adapted to enter corresponding recesses in the opposing portions of the divided insulating member, a fuse strip 95 located between the ribs and between the opposing portions of the divided insulating member and engaging the said ribs at the inner faces and terminals of the same and having its ends extending beyond the ends 100 of the latter with a return bend adjacent to its outer peripheral surface, said insulating member being provided at opposite faces of the fuse strip with longitudinal recesses and a pair of annular caps adapted to embrace the ends of said divided insulating member to bind the parts together, said caps provided with a projecting tongue, 105 adapted to be engaged by the opposing springs of a fuse board.

4. A fuse cartridge comprising an insulating member divided longitudinally, a fuse strip located between said divided portions with its ends extending beyond the respective ends of the latter, and means for binding 115 said divided portions together to form a single unit and to form terminals for the fuse strip, consisting of a member formed of sheet metal shaped to form an annular band surrounding the end of the insulating member with a strip bridging said band across the end of said member.

5. A fuse cartridge comprising a longitudinally divided insulating member, one of the portions of the insulating member 120 being provided with spaced longitudinal ribs and having a central longitudinal recess between the ribs and the other portion

of the insulating member being provided with a longitudinal recess receiving the said ribs, a fuse strip located between the portions of the insulating member and extending between the ribs, the recesses of the said portions of the insulating member forming spaces at the opposite faces of the fuse strip, and means adapted to clamp the

divided portions of the insulating member together to form a single unit. 10

In testimony whereof I sign this specification in the presence of two witnesses.

GEORGE A. CONRAD.
